LABORATORY TABLE UNIT

Charles G. Wall, 15 Montgomery Ave., Bala Cynwyd, Pa.

Filed Apr. 5, 1965, Ser. No. 84,607

Term of patent 3½ years

(Cl. D16—2)

Fig. 1.

Fig. 2.

Fig. 3.

Fig. 4.

Fig. 5.

FIGURE 1 is a perspective view of a laboratory table unit showing my new design;

FIGURE 2 is a top plan view thereof;

FIGURE 3 is a front elevation view thereof;

FIGURE 4 is a right elevation view thereof; and

FIGURE 5 is a rear elevation view thereof.

The left elevation view is a mirror image of the right elevation view.

The dominant features of my design reside in the full line portions.

I claim:

The ornamental design for a laboratory table unit, substantially as shown and described.
